LANTERN

Robert D. Kahn, Rockville Centre, N.Y., assignor to
Fedtro, Inc., a corporation of New York

Filed May 19, 1969, Ser. No. 17,204

The portion of the term of the patent subsequent to
Jan. 30, 1982, has been disclaimed

Term of patent 14 years

Int. Cl. D26—04

U.S. Cl. D48—24

FIG. 1

FIG. 3

FIG. 2

FIG. 4

FIG. 1 is a front elevational view of the lantern;
FIG. 2 is a top view thereof;
FIG. 3 is a view similar to FIG. 1, but rotated 45 degrees with respect thereto, and
FIG. 4 is a bottom view thereof.

I claim:

The ornamental design for a lantern, as shown and described.
